CLAIM

The ornamental design for a radiotelpone accessory connector housing, as shown and described.

DESCRIPTION

FIG. 1 is a front, top, and left side perspective view showing our new design for a radiotelpone accessory connector housing;

FIG. 2 is a front elevational view thereof;

FIG. 3 is a right side elevational view thereof;

FIG. 4 is a bottom plan view thereof;

FIG. 5 is a top plan view thereof;

FIG. 6 is a rear elevational view thereof; and

FIG. 7 is a left side elevational view thereof.

FIG. 8 is a front, top, and left side perspective view showing an alternate embodiment of our new design for a radiotelpone accessory connector housing;

FIG. 9 is a front elevational view thereof;

FIG. 10 is a right side elevational view thereof;

FIG. 11 is a bottom plan view thereof;

FIG. 12 is a top plan view thereof;

FIG. 13 is a rear elevational view thereof; and,

FIG. 14 is a left side elevational view thereof.

The broken line matter in the drawings is for illustrative purposes only and forms no part of the embodiment of FIGS. 1-7.
